(57) **CLAIM**

The ornamental design for an electrical plug contact, as shown and described.

DESCRIPTION

FIG. 1 is a front isometric view of an electrical plug contact showing my new design;

FIG. 2 is a rear isometric view thereof;

FIG. 3 is a top view thereof;

FIG. 4 is a left side view thereof, the right side view thereof being a mirror image thereto;

FIG. 5 is a bottom view thereof;

FIG. 6 is a rear view thereof;

FIG. 7 is a front view thereof;

FIG. 8 is a front isometric view thereof, in use condition;

FIG. 9 is a rear isometric view thereof, in use condition;

FIG. 10 is a top view thereof, in use condition;

FIG. 11 is a left side view thereof, in use condition. The right side view thereof being a mirror image thereto;

FIG. 12 is a bottom view thereof, in use condition;

FIG. 13 is a rear view thereof, in use condition; and,

FIG. 14 is a front view thereof, in use condition.

The broken line of the environment in the figure drawings is included to show unclaimed subject matter only and forms no part of the claimed design.
